OIL BURNER

Ralph R. P. Turner, University Park, Md.

Application May 2, 1939, Serial No. 271,415

5 Claims. (Cl. 158—91)

This invention is directed to an improvement in oil burners designed primarily but not necessarily limited to domestic heating wherein the construction is an extremely simple arrangement of few parts associated with a view to a high heat degree with minimum oil consumption.

The primary object of the present invention is the provision of a simple type pilot, with flame directing cylinder and an external oil-fed flame chamber to which the oil is independently directed and which is under active control of pressure to direct the flame upwardly and beyond the burner proper.

A further object of the invention is the provision of deflectors by which the flame is directed beyond the burner proper in an annular concentrated sheet or ring for effective result.

The invention is illustrated in the accompanying drawing, in which:

20 Figure 1 is a view in vertical section, partly in elevation, of the improved burner.

Figure 2 is a section on the line 2—2 of Figure 1.

The improved burner comprises an outer casing 1, within which is arranged an inner casing 2, the bottom 3 of which is spaced from the bottom 4 of the outer casing. The outer casing is imperforate while the inner casing is perforated with holes of suitable size throughout its full area except the bottom, as indicated at 5.

30 The inner and outer casings 1 and 2 are spaced apart to provide an air space 6, which latter is closed at the upper end, as at 7, and open at the bottom to the space between the bottoms 3 and 4 of the inner and outer casings.

35 Centrally of and resting upon the bottom 3 of the inner casing is a cup-shaped receptacle 8, hereinafter termed the pilot chamber. This receptacle is closed except at the top and is in communication with a liquid fuel pipe 9 leading from an exterior source and opening flush with the bottom of the pilot chamber. It is to be understood, though such parts are not illustrated, that conventional, for example, float controlled means are provided to control the delivery through the fuel pipe 9 so as to maintain a comparatively shallow almost film-like accumulation of fuel in the bottom of the pilot chamber, as indicated at 10.

40 A flame directing cylinder 11 is supported upon legs 10^a, resting on the bottom 3, the cylinder 11 surrounding and in spaced relation to the pilot chamber. The legs 10^a form a space between the bottom of the cylinder 11 and the bottom 3, to form a slight passage between the space between the cup-shaped receptacle 8 and the space between the inner casing and cylinder 11. The

flame directing cylinder extends from the bottom 3 of the inner chamber 2 to a point slightly below the upper ends of these chambers 1 and 2, and is provided at its upper end with bracket arms 12 which support a conical deflector 13, which may be radially fluted. The deflector extends within the flame directing cylinder with its apex 14 below the top of the cylinder, and in the upper edge of the cylinder, there is formed a series of cut-out sections 15 to establish more open relation between the space within the inner casing 2 and the flame directing cylinder.

The upper or free edge 16 of the deflector 13 extends beyond the wall of the flame directing cylinder. In the flame directing cylinder is arranged a baffle 17 open at the center, as at 18.

The flame burning chamber is included between the flame directing cylinder and the casing 2 and is indicated at 20. The upper end of this chamber 20 is provided with a baffle plate 21, preferably secured upon the closed end 7 of the walls of the inner and outer casing, which baffle plate extends towards the deflector 13, the central opening 22 of the baffle 21 affording an outlet from the flame chamber 20 being arranged beneath the outer portion of the deflector. Thus all the flame passing out the opening 22, or as a matter of fact, out of the flame directing cylinder 11 is deflected by the deflector 13 into an annular, comparatively narrow concentrated ring of flame.

30 A fuel delivery pipe 23 extends into the flame chamber near the bottom thereof, the delivery of oil being controlled in accordance with requirements of heat, and hence it is contemplated that a conventional control valve, thermostatically governed, will admit the requisite quantity of fuel to the chamber 20 in accordance with heat demands. A conduit 24 leading from a source of air under pressure opens through the bottom 4 of the outer casing, so that the entire space between the inner and outer casings and within the inner casing may be subjected to air under pressure. Of course, the motor or other means for supplying air under pressure will be controlled by the thermostatic element governing the oil supply to the chamber 20.

40 As thus constructed, it will be understood that there will be a very small quantity of oil or other fuel in the pilot chamber. In order to start the burner, the flame directing cylinder 11 is bodily raised and a lighted match or other igniter dropped into the oil in the pilot chamber. As the vapors from the oil in the pilot chamber rise in the flame directing cylinder, they pass through the openings 15 into the flame chamber 20, into

which latter fuel is being admitted through the pipe 23. The air under pressure admitted through the conduit 24 will pass through the holes 5 creating a more or less vaporous condition of the oil in the chamber 20, also through the passage 10^b to cause the flame from the oil in the pilot chamber to be forced into the chamber 20, and at the same time upwardly through the flame directing cylinder and thereby heat the parts. The conversion action is so rapid that almost as soon as the air is turned on, the vapor in the flame chamber 20 is converted into flame with combustion continuously renewed from the fuel at the bottom of the chamber, and the flame and vapor from the pilot chamber will be drawn upward into the flame directing chamber and forced through the openings 15.

The flame thus generated is directed outwardly through the opening 22 and deflected by the deflector 13, as previously described.

The burner is constructed of metal, has no moving parts in itself and is designed to be inserted as a unit in a furnace or other enclosure according to the purposes for which the heat from the flame beyond the deflector is to be used.

In actual practice, there will be found no flame between the baffle 17 and the fuel in the pilot chamber incident to the pressure of air and the comparatively free upward movement of the same. However, when thermostatic control is effected and the fuel in the chamber 20 is exhausted, the flame in the upper portion of the flame directing cylinder will gradually consume the vapor above the pilot chamber and move downwardly until finally contacting and igniting the oil or other fuel in the pilot chamber, which fuel of course is maintained in constant supply.

The oil burner as a whole may be constructed

of any appropriate material and the parts may be proportioned in any relative sizes commensurate with the work required.

What is claimed to be new is:

1. An oil burner having inner and outer casings spaced at the sides and bottom with the wall of the inner casing formed with a series of openings, a flame directing cylinder arranged within the inner casing and terminating at its upper end short of the upper end of the inner casing, a 10 pilot chamber carried by the bottom of the inner casing and arranged within and spaced from the flame directing cylinder, means for directing fuel in constant limited supply to the pilot chamber, means for directing fuel to the space within 15 the inner casing, and means for directing air under pressure to the space between the casings and through the holes in the wall of the inner casing.

2. A construction as defined in claim 1, including a baffle near the lower end of the inner casing above the pilot chamber to restrict the outlet therefrom, and a conical deflector carried by the flame directing cylinder and extending over the inner casing outlet. 25

3. A construction as defined in claim 1, wherein in the flame directing cylinder is freely movable in the upper direction to permit access to the pilot chamber for igniting the fuel therein.

4. A construction as defined in claim 1, wherein in the flame directing cylinder is interiorly provided with a baffle and with an air passage below the baffle and the flame burning chamber. 30

5. A construction as defined in claim 1, wherein in the upper end of the flame directing cylinder 35 carries a conical deflector which is radially convoluted.
